UNITED STATES PATENT OFFICE

MOSES E. STERN, OF NEW YORK, N. Y.

WINDOW SCREEN

Application filed November 2, 1927. Serial No. 230,463.

This invention relates to window screens and similar devices where it is desired that a simple and compact construction be readily adapted for use to the ordinary sash arrangement of a window.

Heretofore it has been customary in temperate climates to apply window screens early in the spring season in order to prevent flies and other vermin from entering into rooms but permitting an abundance of air circulation. This has normally been done by applying the screen mesh or other net work to wood or metallic frames which are slidably or hingedly mounted upon the frame work of the window. It is an object of this invention to avoid such bulky frame work and to apply a compact construction to the frame of the window which will serve both as a screen arrangement in summer weather, and in winter weather when screens are not necessary, to serve as a wind deflector at the same time overcoming the necessity of removal and storage of the screen. The change in the device necessary to its use as a screen from that of a wind deflector or ventilator is comparatively slight.

Another object of this invention is to provide a window screen or similar device which is movable with the window in its sliding action to open or close and is attached thereto at or near its bottom edge so that when the window is in the closed position the screen is retracted and will not affect or obscure the light in any way.

A still further object of this invention is to arrange the window screen with quickly detachable fastenings for securing it to a sash member of a window.

A still further object of this invention is to simplify the application of screens to a window so that a standard size screen apparatus may be readily adjusted to accommodate or fit a particular sized window with a minimum of structural changes.

Another object of this invention is to improve the operation of window screens and the like in which the screen is attached to one of the movable sash members and retracted from, or rewound upon, a spring-tensioned roller member having a housing

for protecting it. By the use of simple and properly arranged end pieces the screen as a whole may be readily applied to the frame work of a window with a minimum of effort.

Further and more definite objects will appear in the following specification, claims and drawing in which—

Figure 1 shows a window frame and sash to which is applied my improved form of screen, part of the ventilating cover being broken away to show the internal construction of the screen roller,

Figure 2 shows a side sectional view along the line 2—2 of Figure 1;

Figure 3 shows a detailed sectional view on an enlarged scale along the line 3—3 of Figure 2;

Figure 4 shows another sectional view showing one end of the ventilating enclosure of Figure 3 along the line 4—4;

Figure 5 shows the other end of the ventilating enclosure in section along the line 5—5 of Figure 3;

Figure 6 shows another detailed view in section along the line 6—6 of Figure 1;

Figure 7 shows a detail of the ventilating portion of the ventilating enclosure on an enlarged scale along the line 7—7 of Figure 1;

Figure 8 shows a sectional view along the line 5—5 of Figure 3 except for the fact that the screen element is in position where it is not being used and the arrangement is adjusted for use as a ventilator;

Figure 9 shows an enlarged portion of the screen attachment element and a detail of a handle for removing it from its fastening on the sash member;

Figure 10 shows a view of the end of the screen by itself which is attached to the sash element, indicating the relation of the attachment holes and the handles; and

Figure 11 shows a view on a reduced scale of the cover element for covering the screen and protecting it from use when used as a screen and not a ventilator.

Referring now to the drawings and more particularly to Figures 1 and 2 the window frame construction 1 is mounted in the customary way upon the frame work 2 of a house or similar enclosure. The windows 3

and 4 slidably mounted with cords 5 for counterbalancing their weight and maintaining them in fixed position due to the frictional engagement of the sashes 6 with the frame of the window. Attached to the ledge 8 by means of thumb screws 9 or otherwise, is a cover or ventilating enclosure 10. Within this enclosure is mounted for rotation the roller 11 and the idler 12, mounted at their ends and arranged in plates 13 and 14 more particularly shown in Figure 3. The cover 10 may be made quickly detachable by making the holes 15 elongated of sufficient size to permit passage of the screws 9.

The roller 11 is spring-tensioned by apparatus to be described further on and is surrounded by the screen or other equivalent material 16. The end is provided with a ferrule arrangement 17 clamped, riveted or otherwise secured to the end of the screen to maintain it in rigid position when mounted upon the lower sash 6. This mounting of the ferrule 17 may be accomplished in a plurality of ways such as for instance a wing nut arrangement, snap fasteners or ordinary round-headed screws as shown at 18. In the case of these screw fastenings, the ferrule 17 may be provided with holes 19 which are slightly larger than the head of the screws 18 and being in proper spaced relation with each other and the screws, the head may be slipped through these holes and the ferrule will then be caught by the shoulder in back of the heads, the tension of the spring in the roller 11 maintaining the ferrule in the proper position on the sash 6.

When the window is in closed position the screen will be rolled up on the roller 11 and when it is opened as shown in Figures 1 and 2 the screen will be withdrawn from the ventilating container 10 to an upward position. The proper horizontal position of the screen with the window frame is maintained by the use of an idler roller 12 about which the screen is withdrawn. This is preferably located at such points that the screen may be directly drawn in a perpendicular direction without undue tension and strain. This position may be directly underneath the fastening of the ferrule or slightly to the right of that position as indicated in the sectional view of Figure 2, inasmuch as the screen tends to assume a slightly bellying position from the rolling effect produced by the rollers.

In order to keep the screen 16 in proper alignment and prevent flapping or bellying at unsupported points along the edge, a strip 21 and 22 may be applied at the opposite edges of the window frame for guiding the screen. The shape of this strip is more clearly shown in Figure 6 and if desired a piece of sheet metal bent into an angular form as at 23 and 24 may be used as a backing piece for the screen 16, thereby providing slots between the sheet metal pieces 23 and 24 and the wood

strips 21 and 22. The proper clearance between these pieces can be adjusted as desired but sufficient should be provided so as to prevent undue binding on the screen. These strips and guide pieces may be held in position by means of screws or brads 25 and 26. It is obvious that these pieces may be made to fit any standard type of window and from materials easily procured in the market.

The roller 11 may be supplied with a special attachment nailed or screwed to one end as shown at the right of Figure 3. A pin or stub shaft 28 is arranged with a shoulder 29 and an integral lug portion 30 for coacting with the spring 31. A backing plate 32 may be screwed or nailed to the body portion of the roller 11 at 33 both for the purpose of forming a bearing for the shaft 28 and to maintain the spring 31 in the proper spaced relation to prevent binding. The hole 34 may provide sufficient clearance for the end of the shaft 28 to obviate undue friction. The outer end of the shaft is supported by the front plate 35 having a hole through which the shaft 28 projects and is loosely guided thereby. This shaft has also a flat end portion 36 for coacting with one of the end plates 14. The other end of the spring 31 is secured by means of a lug 37 struck out of the outer tubular covering member 38 which supports the end plate 36. This plate may be pushed over the roller 11 a sufficient distance as to effectively prevent sideways movement. The other end of the roller may be furnished to the user without attachment thereon and in order that it may be properly fitted to the location where it is to be used. After cutting off the roll at the correct point a cap 40 may be applied to the end. A pivot pin 41 having a shoulder 42 to take up the side thrusts of the roller is then inserted in the hole at the center of the cap and driven in place.

After these attachments have been made the screen 16 may be cut off in the proper size and tacked or otherwise secured to the roll. The roller 12 is furnished in the form of a length of metallic tubing which may be readily cut off at the proper point, end bearings being formed at 43 and 44 in the shape of cylindrical lugs riveted or otherwise secured to the end plates 13 and 14.

The only other element necessary to be fitted to a particular width of window is the outer casing or ventilating cover 10. This may be cut off by any suitable means to fit the location where it is to be used and screwed to the window ledge as previously described by means of screws 9.

In connection with this cover member 10 there may also be used a baffle or backing plate 46 which is formed in the shape indicated in Figure 11 with ears 47 and 48. This plate 46 will also have to be fitted to the particular

window to which it is used and may be cut off as desired.

The end plates 13 and 14 are used to secure the whole assembly to the window frame prior to applying the cover 10 and the backing plate 46. These end plates are slightly different in construction as will be clear in connection with Figures 4 and 5 respectively. The end plate 13 is provided with a slot 60 in the horizontal direction and another slot 50 in a vertical direction. There is also a hole 49 arranged at or near the center to accommodate the pin 40 of the roller 11. The slot for plate 46 extends downwardly to the point indicated at 50, leaving the upper end of the slot open to permit free access thereto. The plate 14 is substantially similar to the plate 13 except that the roller supports 44 and 43 extend from opposite sides of these plates making one of them, so far as the parts heretofore described are concerned, of substantially opposite construction. In addition to the slots of end plate 13 there is also provided in the plate 14 another slot 51 arranged to permit withdrawal and replacement of the roller 11 in a manner which is common to the shade roller art. If desired a similar slot may be provided in plate 13 but this is not essential.

These plates 13 and 14 may be fixed with relation to the window frame by means of screws 52 and 53. They may be horizontally adjusted by loosening the screws and sliding off the plates. In these figures it will be seen that the guide strips 21 and 22 are located at the bottom position and the roller 12 is adjusted by moving the plates 13 and 14 to the proper position so that the screen 16 will be easily withdrawn from the roller 40 and coat with the rest of the window construction.

The upper part of the screen 16 being provided with a ferrule or binding strip 17 as previously explained and shown more clearly in Figure 10, is constructed to be readily attached or displaced from the lower part of the window frame. To permit such attachment the handles 54 and 55 may be used. A detail of these handles and the method of construction is shown in Figure 9. A slot 55 at the top of the ferrule is made so as to allow the handle 54 to be swung into a vertical position or a horizontal position, the horizontal position being shown more clearly in Figure 8.

The top portion 62 of the cover 10 is provided with a series of holes 61. These holes may be arranged in any manner or design so as to provide free access and circulation of the air. During the ordinary use of the screen in the summer time the binding strip 17 is attached to the window sash as shown in Figures 1 and 2. This attachment may be made by any suitable means, as previously described, and the window may be raised or

lowered at will at the same time withdrawing or permitting retraction of the screen upon the roller 11 through the action of the spring 31. For use as a screen the cover plate 46 is positioned within the slot ending 70 at 50 to serve both as a guide to the screen by preventing clamping or undue displacement of the screen adjacent this portion as well as to protect the screen and roller.

In colder weather or when it is not desired to use the screen the protecting plate 46 may be withdrawn from the slot and the extending ends 58 formed by the extension of the ferrule 17 beyond the edges of the screen 16 may be positioned in these slots 80 so that the screen will take the position as indicated in Figure 8. When arranged in this position the window sash may be raised until it occupies the position at 59 where the air will be permitted to circulate as indicated by the arrows through a portion of the screen and through the holes 51 in an upward direction so as to cause no direct draught in the room in which the apparatus is used.

It can thus be seen that a convenient and compact arrangement is provided which may be readily fitted to different widths of windows with a minimum of effort, that will provide first a screening arrangement in warm weather and ventilating arrangement in cooler weather without inconvenience. Slight modifications can be made of the various parts as for instance the rear protection plate 46 may be done away with where only screening is desired. In order to retain the cover 10 more firmly in position the end may be extended out to overlap the end plates 13 and 14 throughout the extent of the perpendicular portion, while the horizontal portion may be made to fit closely within the confines of the end plates 13 and 14. A series of struck-up portions may be made to serve as a guide for the side edges of the horizontal portion if desired, but these are not shown, it being understood that any well known means for securing this portion but consistent with the easy replaceability of the cover may be used. Also this cover plate may be attached directly to the end pieces 13 and 14 by any convenient quickly detachable means. The apparatus may also be readily installed at the top of the window frame as well as the bottom with equal efficiency.

It is not intended to be limited to the exact disclosure herein but deviations commensurate with the following claims is intended to be covered hereby.

I claim:

1. A window screen comprising end plates for fitting a window frame with upper and lower sills and having rollers positioned between said end plates; in which, the end plates have straight edges positioned against

one of the sills and attached to said frame by means of a screw passing through a horizontal open ended slot in each of said plates for adjusting said plates toward and away from the window.

5. 2. A window screen comprising end plates for fitting a window frame with upper and lower sills and having rollers positioned between said end plates; in which the end plates have straight edges positioned against one of the sills and attached to said frame by means of a screw passing through a horizontal open ended slot in each of said plates for adjusting said plates toward and away from the window, said end plates having bearings in the form of projecting lugs formed at one corner of each of the plates.

20. 3. A window screen comprising end plates for fitting a window frame with upper and lower sills and having rollers positioned between said end plates; in which the end plates have straight edges positioned against one of the sills and attached to said frame by means of a screw passing through a horizontal open ended slot in each of said plates for adjusting said plates toward and away from the window, and a cover enclosing two sides of the roller, one side of which is perforated to permit the circulation of the air.

25. 4. A window screen comprising end plates for fitting a window frame with upper and lower sills and having rollers positioned between said end plates; in which the end plates have straight edges positioned against one of the sills and attached to said frame by means of a screw passing through a horizontal open ended slot in each of said plates for adjusting said plates toward and away from the window, said end plates having bearings in the form of projecting lugs formed at one corner of each of the plates, and a cover enclosing two sides of the roller, one side of which is perforated to permit the circulation of the air.

45. 45. In testimony whereof I have signed this specification this 31st day of October, 1927.

MOSES E. STERN.
